DESIGN FOR A MAN'S JACKET

Benjamin Gewertz, New York, N. Y.

Application May 27, 1942, Serial No. 107,021

Term of patent 3½ years

To all whom it may concern:

Be it known that I, Benjamin Gewertz, a citizen of the United States of America, residing in New York city, county of New York, and State of New York, have invented a new, original, and ornamental Design for a Man's Jacket, of which the following is a specification, reference being had to the accompanying drawing, forming part thereof, wherein,

I claim:

The ornamental design for a man's jacket, substantially as shown.

BENJAMIN GEWERTZ.
